UNITED STATES PATENT OFFICE

114,995

DESIGN FOR A TENNIS RACKET PRESS

George J. Graham, Merion, Pa.

Application May 15, 1937, Serial No. 69,362

Term of patent 7 years

To all whom it may concern:

Be it known that I, George J. Graham, a citizen of the United States, residing at Merion, in the county of Montgomery and State of Pennsylvania, have invented a new, original, and ornamental Design for a Tennis Racket Press, of which the following is a specification, reference being had to the accompanying drawing, forming part thereof.

Figure 1 is a top plan view of a tennis racket press, showing my new design.

Figure 2 is a bottom plan view thereof; and

Figure 3 is an edge elevational view.

I claim:

The ornamental design for a tennis racket press, as shown.

GEORGE J. GRAHAM.
